UNITED STATES PATENT OFFICE.

JOHN W. P. BUNNING, OF PHILADELPHIA, PENNSYLVANIA.

COMBINATION-GARMENT.

No. 874,487.

Specification of Letters Patent.

Patented Dec. 24, 1907.

Application filed May 28, 1906. Serial No. 319,018.

To all whom it may concern:

Be it known that I, JOHN W. P. BUNNING, a citizen of the United States, and a resident of the city and county of Philadelphia, State 5 of Pennsylvania, have invented certain new and useful Improvements in Combination-Garments, of which the following is a full, clear, and exact disclosure.

My invention relates to combination garments in which two or more usually separate pieces of wearing apparel are combined into a single garment, and my invention especially relates to a garment having a waist or body portion, a skirt portion and a drawers 15 or pants portion, all combined into a single article of wearing apparel.

Among the objects of my invention are the following:—To make a combination or union garment which can be stepped into 20 rather than slipped over the head of the wearer, to enable the same to be readily and easily put on or taken off without disarranging the hair, to avoid the bunching of the several parts of the garment at the waist of 25 the wearer, to give a smooth fit and appearance; to facilitate and save expense in the making, washing and laundering of the same; to arrange and secure the parts of my combined garment together in such a manner 30 as will permit the free movement of the legs of the wearer without altering or changing the general appearance or hang of the skirt and to prevent the skirt from creeping up the back.

Further objects of my invention are to 35 make a combined garment either out of one integral piece of fabric or of two or more separate pieces stitched together at the desired 40 points, and to make a garment which, with slight changes, can be made either to closely 45 fit the body, to retain all the bodily heat from head to foot, or can be made loose and comfortable for hot weather, and at the same time completely cover the body of the wearer.

Further objects of my invention will appear in the specification and drawings forming a part of this specification, in which corresponding parts are denominated by the 50 same reference characters.

Referring to the drawings, Figures 1 to 4 inclusive illustrate a garment made in accordance with my invention, from one integral piece of suitable fabric. Fig. 1 shows

the way in which the fabric is cut and the lines on which the same is folded to form the combined garment; Figs. 2 and 3 show the fabric illustrated in Fig. 1 as folded into the desired shape to form the garment, and Fig. 4 is a sectional view of the complete garment 55 at a short distance below the waist line of the same; Figs. 5, 6 and 7 show another modified form of my improved combined garment, in which the same is made of four pieces of fabric, suitably cut and stitched together, 60 Fig. 5 showing such garment with the various parts properly secured together, Fig. 6 showing how the same is turned in order to be worn and Fig. 7 being a sectional view on the line 7—7 of Fig. 6; Fig. 8 is a further modified 65 form of my invention in which the garment is made out of but two pieces of fabric; Fig. 9 is a sectional view on the line 9—9 of Fig. 8; Figs. 10 and 11 show a child's garment made in accordance with my invention; 70 Figs. 12 and 13 show how pajamas are made embodying my invention, and Figs. 14 and 15 show a child's garment, provided with means for attaching a separate or outside 75 skirt to the same.

Referring now to Figs. 1 to 4 inclusive, at the ends of two diameters 1—2 and 3—4, at right angles to each other and intersecting at the center 5, a circular piece of cloth A is cut inwardly for a short distance as to the points 80 6, 7, 8, 9. In Fig. 1, the fabric is shown as folded back on either side of these cuts, and the outer corners of the fabric as cut are indicated by 10, 11, 12, 13, 14, 15, 16, 17. 18—19 and 20—21 are two other diameters at 85 right angles to each other and bisecting the angles formed by the diameters 1—2 and 3—4. The cloth is cut on the diameter 18—19 from the point 5 to the point 22 to form the opening in the front b in the body or waist 90 portion B, and on the diameter 20—21 from the points 23—24 to the center 5 to form the top edges of the waist or body portion and the inside of the drawers legs. The points 25, 26, 27 and 28 are laid out substantially 95 equi-distant from the center 5 and from points on the waist line of the garment to be formed. The cloth is then cut from the points 25 and 26 to the points 27 and 28 respectively about the point 5 as a center, and the intersection of these curved cuts with the 100 cut between the points 23 and 24 forms angles or corners in the fabric, which are desig-

nated by 29, 30, 31, 32, 33, 34, 35 and 36. Between the points 25 and 30; 26 and 34; 27 and 31; and 28 and 35 another cut is made, curved inwardly, as at 37, 38, 39 and 40, to give the proper shape to the waist portion of the garment. When the fabric has been cut in the manner above indicated, the portion bounded by the points 27, 39, 31, 35, 40 and 28 will form the front *b* of the waist portion and the portion bounded by the points 30, 37, 25, 26, 38 and 34 will form the back *c* of the waist portion; the part bounded by the points 15, 9, 27, 28, 8 and 14 will form the front *d* and between the points 10, 6, 25, 26, 15 7 and 11 the back *e* of the skirt *C*; that bounded by the points 17, 6, 25, 29, 23, 32, 27, 9 and 16 and that bounded by the points 12, 7, 26, 33, 24, 36, 28, 8 and 13 will form respectively the legs *f*, *g* of the drawers *D*. The 20 manner in which these various parts are folded is plainly indicated in Figs. 1 and 2; that is to say, the middle of each drawers leg portion is folded downwardly on the diameter 20—21 and the edges 6—25 and 9—27 are brought 25 together on one side and the edges 7—26 and 8—28 are brought together on the opposite side of the diameter 18—19. The portions *b*, *c* are folded together, bringing the points 25 and 26 adjacent the points 30 30 27 and 28. After having been folded in the manner above indicated, the edges 27, 9, 15 and 25, 6, 10 are sewed together to form the outside seam of the skirt on one side, and the edges 28, 8, 14 and 26, 7, 11 are similarly 35 sewed together on the opposite side. This seam also forms a part of the outside seam of each drawers leg, the bottom of each leg being formed by sewing together the edges 9—16 and 6—17 on one side and the edges 8—13 40 and 7—12 on the opposite side. The adjoining edges of the back and front portions of the waist are also stitched together on opposite sides; that is to say, by joining the edge 31—39—27 to the edge 30—37—25 and the edges 35—40—28 to the edge 34—38—26. The points 32 and 36 at the top of each leg are adjacent each other, and form the middle 45 of the front of the waistband of the drawers, and the points 29—33 are also adjacent on 50 the back and form the middle of the back of the waistband of the drawers. These points may be connected to each other in any suitable manner, as by a button, hook or string. The garment formed and sewed in the manner thus set forth then combines three pieces of clothing; a waist portion or corset cover *B*, a skirt portion *C* and a drawers or pants portion *D*, the legs of the drawers being attached to the skirt along the outside of the 55 leg *f* from the point 25—27 to the point 6—9 and of the leg *g* from the point 26—28 to the point 7—8. The inner edges 29—23—32 of the drawers leg *f* may be stitched to the opposite edge 33—24—36 of the leg *g*, or the

two edges may be left open, as desired. 65 Shoulder straps *h*—*k* may be secured to the top of the body portion of the corset cover, as plainly shown in Fig. 3, and the edges of the garment may be ornamented with lace or ribbons, in any suitable manner. 70

While I have described the garment as being folded and cut on diameters at right angles to each other, it is of course understood that the angles which these diameters make with each other may vary as required. For 75 instance, the front and the back of the waist and skirt may require more than one half of the material in the circular piece of cloth *A*, and this could be provided for by laying out the diameters 1—2 and 3—4 so that less material would be used for each of the leg or drawers or pants portion, and more would be allowed for the skirt and waist. 80

The garment as above described is provided with additional shoulder straps or suspenders *M*, the lower ends of which are attached by buttons 45 to the waistband at the front and back of the drawers to support the same, and the lower ends of the suspenders may be provided with stocking supporters *N* 90 on both the front and the back thereof, as desired. 95

Referring now to the modification shown in Figs. 5 to 7 inclusive, I form the front of the corset cover and skirt all of one piece of material, as indicated by *E* and the back of the corset cover and skirt by a similar piece *F*. The front and the back may be of the same size and shape or the back may be narrower than the front, depending upon the 100 figure of the wearer. The opposite edges of these two pieces *E* and *F* are stitched together at the edges 35—28—8—14 and 31—27—9—15 as well as across the top of the shoulder straps *h*—*k*, as shown at 41 and 105 42. To the outside of the body portion and just below the waist line, the drawers legs *f*, *g* are secured to the side of the skirt by sewing, as indicated at 28—8 and 27—9. Each drawers leg is made of a single piece of cloth 110 folded on the lines 28—8—13 and 27—9—16 respectively, and the opposite sides of each leg are stitched together to form seams 23—20 and 24—21 on the inside lower end of each leg. After these parts have been 115 assembled as shown in Fig. 5, the garment is turned inside out, so that the legs are inside of the skirt portion. The top of each drawers leg is provided with a waistband *m* and they are held around the waist of the 120 wearer by any suitable means, as by strings, buttons or hooks. The garment in the position in which same is worn is shown in Fig. 6. The adjacent edges 29—23—32 and 33—24—36 of the inside of each drawers leg may 125 be left open as indicated in the drawings, or they may be sewed together or buttoned, as may be desired. In Fig. 7 the pieces of

material used and the way in which the front and back of the skirt are joined to each other and to the drawers legs is shown on an enlarged scale.

5 In the modification shown in Fig. 8, the front of the corset cover B and skirt C and one side of each drawers leg f, g are made of one piece of cloth G, and the back of the same parts of the garment are made from 10 another entire piece H. In this instance, the major portion of the shoulder straps may be integral with the back portion H and are brought forward over the shoulders, and buttoned or hooked in the front, as shown at

15 43—43. To form the garment, then, it is merely necessary to stitch together the outer edges of the waist portion from the points 35—31 to the points 28—27 respectively, and to continue the stitching through the 20 point 8 to the point 14 on the one side and through the point 9 to the point 15 on the other side. In other respects the garments shown in said figure is similar to that shown in Fig. 5.

25 The child's garment illustrated in Figs. 10 and 11 may be made in any of the ways previously described. In this instance, however, the waist B is preferably provided with sleeves L and the opposite inner edges of the 30 legs would be preferably united for the whole or a part of the length thereof by stitching or by buttons to form pants. The waist is further provided with suspenders M, which may be secured to the waist at the shoulders 35 by stitching, as shown at 44—44, and the lower ends may be buttoned to the waistband as at 45. Also buttoned to the waistband are garters N of any suitable description.

40 The pajamas shown in Fig. 12 are also made in accordance with the invention previously described. The pants are secured at their outer seams from the waist portion of the jacket to the bottom of the skirt of the 45 same as at 27—9 and 28—8, and the top of the pants is provided with a suitable waistband m, by which the same are secured to the body of the wearer. The inner edges of the legs may either be united by stitching or 50 by a series of buttons 46 extending from the front to the back. The jacket or waist portion may be left open from the neck downward for the entire length of the same or for a part of the distance only. In order to support the pants of the pajamas at the back as 55 well as at the sides or hips and to prevent the coat from crawling up the back, I may provide a loop r at the middle of the back on a line with the waistband of the pants or 60 drawers. Through this loop I pass the strings at the waistband of the pants and then tie the same together as plainly shown in Fig. 12.

Figs. 14 and 15 show a combined garment suitable for children, in which the waist or body portion is provided with an additional band n, to which an outer skirt O may be attached. This feature of the invention is, of course, applicable to the other forms or modifications previously described, that is to say the combined corset cover, skirt and drawers illustrated in Figs. 1 to 9 might be provided with a waistband to which an under skirt might be attached. The combined or union garment as above described can be readily 70 adapted to many purposes, in view of the manifest advantages of the same. It may be made of suitable materials for bath robes, bathing suits, lounging robes and winter underclothing, or of light cotton or silk, in 75 which instance the wearer would be completely clothed in the fewest possible pieces. The shape of the drawers or pants portion is capable of great variation without departing from the spirit of my invention, since they 80 may be made full or tight fitting, open or closed or partly open or partly closed, according to the use to which the garment is to be put.

85 While I have described a number of various modifications of my invention, I do not desire to be limited to any one or all of the forms disclosed, since by my invention many different garments may be made which would embody the same, and all are fully within 90 the scope of my invention so long as they fall within the terms of the appended claims.

95 Having thus described my invention, what I claim as new and desire to protect by Letters Patent of the United States is:—

100 1. A combined skirt and drawers formed integrally from a single piece of fabric.

105 2. A combined garment formed integrally from a single piece of fabric comprising a waist portion, a skirt portion and leg portions, the sides of each leg being permanently attached to the side of said skirt below the waist line.

110 3. A combined garment formed integrally from a single piece of fabric comprising a skirt portion and leg portions, the outside of each leg being attached to the skirt for a part of its length, and means at the top of each leg for securing the same to the waist of the wearer.

115 4. A combined garment comprising a skirt portion and leg portions, the outside of each leg being attached to the skirt for a part of its length, and a waistband separate from the skirt permanently attached to the top of the 120 leg portions and means separate from said waistband to support said skirt.

125 5. A combined garment formed integrally from a single piece of fabric comprising a waist, a skirt and legs stitched to the side of the skirt by a single seam.

6. A combined garment comprising a skirt and legs, the outside of the legs being secured to the inside of the skirt by a single seam, the top of said legs being provided with a waistband independent of the skirt and means to support said skirt independently of said waistband. 65
7. A combined garment comprising a waist, a skirt and drawers, the waist and skirt being made continuous, and the drawers being attached for a considerable part of their length to the sides of the skirt, a waistband to support said drawers and means to support said skirt independently of said waistband. 70
8. A combined garment comprising a skirt and separated drawers legs, the outside of each leg being secured for a considerable part of its length on the outside seam thereof to the inside of the skirt, and means at the top of the drawers legs for securing the same to the waist of the wearer and means to support said skirt independent of said leg supporting means. 75
9. A combined garment, comprising waist, skirt and leg portions, permanently attached together, the inner upper edges of the leg portions being united at the top of the front and back and attached to said skirt lengthwise of the leg and along the outer seam thereof, said legs being provided with a waistband and means independent of said waistband for supporting said skirt. 80
10. A combined skirt, waist and drawers made from a single integral piece of fabric. 85
11. A combination garment made out of a single integral piece of fabric comprising a skirt, a waist and legs, the legs being formed by folds in the side of the skirt. 90
12. A combination garment comprising a circular skirt, and legs secured to the sides of the skirt lengthwise of said leg and along the outer seam thereof, each leg being formed by a fold in the side of the skirt, said legs being provided with a waistband and means for supporting said skirt independently of said waistband. 95
13. A combined garment comprising a waist, skirt and leg portions, the back of the waist being provided with shoulder straps fastened to the front of said waist, the legs being united to the skirt for a considerable part of the length of said legs and along the outer seam thereof. 100
14. A combined garment comprising waist, skirt and legs, the outside of each leg being stitched to the side of the skirt, means for securing the legs to the waist of the wearer and suspenders attached to the inside of the waist. 105
15. A combined garment comprising waist, skirt and leg portions permanently secured together, the said legs being provided at the top with a waistband and suspenders at- 110
- tached to the inside of said waist, and attached to said waistband. 115
16. A combined garment comprising waist, skirt and leg portions, permanently secured together, the said legs being provided at the top with a waistband and suspenders attached to the inside of said waist, and attached to the front and back of said waistband. 120
17. A combined garment comprising waist, skirt and leg portions permanently secured together, the said legs being provided at the top with a waistband and suspenders attached to the inside of said waist and attached to said waistband, said suspenders terminating in their lower front ends in stocking supporters. 125
18. A combined garment comprising a waist portion, skirt portion and leg portions, the legs being an original undetached part of the skirt. 130
19. A combined garment comprising a skirt and legs, the outside of the legs lengthwise thereof being attached to the inside of the skirt by a single seam, and the inside top edges of the legs having means for attaching the same together, a waistband for supporting said legs and means for supporting said skirt independently of said waistband. 135
20. A combined garment comprising a waist, skirt and drawers, the outside of the legs lengthwise thereof being secured to the side of the skirt and each leg formed by a fold in the side of the skirt, a waistband for supporting said legs and means independent of said waistband for supporting said skirt. 140
21. A combined skirt, waist and drawers, formed from a circular piece of fabric, the said piece having central incisions to form the waist. 145
22. A combined skirt, waist and drawers, formed from a single piece of fabric, the said piece having central incisions to form the waist and substantially radial folds to form the drawers. 150
23. A combined skirt, waist and drawers formed from a single piece of fabric, said fabric having opposite central curved incisions, a transverse incision between said curved incision for forming the two sides of the waist, and substantially radial folds to form the drawers. 155
24. A combined garment made of a single integral piece of fabric, comprising a skirt, a waist and legs, each leg being formed by a fold in the skirt, said legs being part way detached at top and bottom from the skirt. 160
25. A combined garment comprising a waist, a skirt and drawers, the waist and skirt being made continuous, and the drawers being attached at the outside of the leg portions to the skirt, with a vent at the bottom to facilitate better adjustment. 165
26. A combined garment comprising waist, 170

skirt and leg portions formed from a single integral piece of material, the inner, upper, adjacent edges of the leg portions being vented to form closed pants or drawers.

5. 27. A combination garment comprising a circular skirt and legs secured to the sides of the skirt, each leg being formed by a fold in the side of the skirt, said skirt having a per-

manent waistband with means to which can be secured another skirt.

In witness whereof, I have hereunto set my hand this 26th day of May, A. D. 1906.

JOHN W. P. BUNNING.
